UNITED STATES PATENT OFFICE.

DAVID N. JONES, OF MINNEAPOLIS, MINNESOTA.

ENGINE.

1,206,715.

Specification of Letters Patent. Patented Nov. 28, 1916.

Application filed December 27, 1915. Serial No. 68,772.

To all whom it may concern:

Be it known that I, DAVID N. JONES, a citizen of the United States, residing at Minneapolis, in the county of Hennepin and State of Minnesota, have invented certain new and useful Improvements in Internal-Combustion Engines; and I do declare the following to be a full, clear, and exact description of the invention, such as will enable others skilled in the art to which it appertains to make and use the same:

My invention which relates to improvements in internal combustion engines has for its object to provide a machine of this class which although being of comparatively simple and inexpensive construction will be highly efficient and durable, provision being made whereby all gears are incased to allow them to run in oil, the casings being so constructed as to serve as supports for the entire engine.

With the foregoing general object in view, the invention resides in certain novel features of construction and in unique combinations of parts to be hereinafter fully described and claimed, the descriptive matter being supplemented by the accompanying drawings which constitute a part of this application and in which:

Figure 1 is a horizontal sectional view partly in elevation; Figs. 2, 3, 4 and 5 are longitudinal sectional views as seen on the planes represented by the lines 2-2, 3-3, 4-4 and 5-5 of Fig. 1; Fig. 6 is a vertical transverse section taken on the planes of the line 6-6 of Fig. 1; Fig. 7 is a detail horizontal section taken on the line 7-7 of Fig. 6.

In specifically describing the construction shown in the drawings above briefly described, similar reference characters will be placed on corresponding parts throughout the several views and reference will be herein made to the numerous elements by their respective indices. To this end, the numeral 1 designates a flat casing in substantially the form of an equilateral triangle standing upright on one of its corners, said corner being provided with a horizontally elongated base 2 to rest on a floor or the like. The other two corners of the casing 1 are rounded as disclosed at 3, being extended upwardly a slight extent above the top of said casing, and the inner flat side 4 of the latter is formed with a pair of circular openings 5 which coincide with the rounded

corners 3 on approximately the same radii therewith.

The inner side 4 is preferably made removable, being secured to the remainder of the casing by machine screws or the like 6, some of which enter the base 2, while others are threaded into ears 7 formed integrally with and depending from the top of the casing. The flat upright outer side 8 of the casing in question is shown as formed integrally with the three edges of the latter, being in the form of a solid imperforate plate.

Extending laterally in horizontal directions from the upper corners of the casing 1, is a pair of cylindrical crank cases 9, one end of said cases being closed and enlarged as shown at 10 and inserted snugly into the openings 5 and the rounded corners 3, the enlargements 10 being secured in place by machine screws 11 passing through the upwardly converging edge walls of the casing 1 and through the top of said casing.

The other ends of the crank cases 9 are closed as seen at 12, said ends being secured by screws or the like 13 to the upright inner side 14 of an additional upright flat casing 15, this casing being preferably of rectangular formation elongated horizontally. As clearly shown in Figs. 5 and 6, the casing 15 is of less height than the casing 1 and is provided at its center with a single leg 16 adapted to rest on the floor or other support used for the engine. The outer side 17 of the casing 15 is secured removably in place by screws 18 whereby it may be detached at will.

Both crank cases 9 are formed of upper and lower semi-cylindrical sections secured together not only by the means described at the ends of said cases, but by upright screws or the like 19 extending through bosses 20 cast integrally with the aforesaid sections and extending laterally therefrom.

Interposed between the two casings 1 and 15 is a horizontal cylinder 21 whose ends are flanged and secured by screws or the like 22 to the inner adjacent portions of the cases 9, such portions being formed with bosses 23 for this purpose. The center of the cylinder 21 is equipped with any preferred type of valve casing 24 in which intake and exhaust valves 25 and 26 are positioned, the stems 25^a and 26^a of said valves depending below the casing and the cylinder as shown clearly in Figs. 3 and 6. These

stems are operated intermittently by means to be described.

- Operating within the cylinder 21 is a pair of pistons 27 connected by rods 28 with cranks 29 formed on crank shafts 30 which are disposed one in each crank case 9, being mounted in appropriate bearings in the ends 10 and 12 and in other bearings carried in transverse partitions 31 with which the cases 10 are equipped. One end of the shafts 30 extends into the casing 1, spiral gears 32 being keyed thereon and disposed in said casing, these gears being meshed with a larger spiral gear 33 also positioned in the casing 1 and secured to a power shaft 34 which passes transversely through both casings 1 and 15 below the cylinder 21. Since the improved engine is of the four-cycle type and since the valves 25 and 26 are operated directly from the power shaft 34, it is essential that the latter travel at one half the speed of the crank shafts 30. This end is attained by the proper ratio between gears 32 and 33.
- The upright horizontally spaced stems 25 and 26 of the intake and exhaust valves 25 and 26 respectively, are provided with rigid arms 35 projecting horizontally from the lower ends of said stems into parallel relation, said arms being received between guide fingers 36 carried on a rigid arm 37 projecting horizontally from a longitudinally disposed bar 38 secured at its ends to the lower sides of the bosses 23. Thus, the arms 35 will be guided in their vertical movement, such movement being imparted thereto by appropriate cams 39 secured on the power shaft 34.
- One of the crank shafts 30 projects into the casing 15 and is provided with a gear 40 meshing with an intermediate idle gear 41 which in turn meshes with a third gear 42 secured on the end of a transverse horizontal magneto and timer shaft 43, the three gears 40, 41 and 42 being disposed in the aforesaid casing 15. As clearly shown in several of the figures of the drawings, the shaft 43 is positioned in a plane above the cylinder 21. This location is preferable though not essential, it being obvious that any preferred type of timer may be operated by said shaft and that if desired, a magneto may be driven thereby.
- In operation, as the two pistons 27 first recede from each other, the intake valve 25 will be opened, thus causing such pistons to draw a charge of explosive mixture from the carburetor C into the cylinder 21. This having been done, the pistons 27 travel toward each other to compress the charge of mixture, and when said pistons assume the relation shown in Fig. 2, ignition is effected by an appropriate spark plug P disposed centrally between the ends of the cylinder. It is to be observed that when this occurs,
- both cranks 29 are past dead center, one being raised past a medial line while the other is lowered beyond such line. Thus, when expansion within the cylinder takes place, it will act in such a manner on both pistons as to rotate the crank shafts 29 under power, the two shafts traveling in synchronism due to the single gear 33 meshing with the gears 32 which are secured to the ends of said shafts. By the time the power stroke of the engine is completed and the pistons again travel toward each other, the exhaust valve 26 has been opened by its cam and scavenging of the cylinder takes place, thereby placing it in readiness for the reception of a new charge when the pistons again recede from each other.
- From the foregoing, the construction and manner of operation of the improved machine will be readily understood and it will be obvious that the machine incorporates a number of improved features. Among the most important of these is the fact that the two casings 1 and 15 not only serve as supports for the entire engine, but as housings for the gears confined therein. The casing 1 may well be partially filled with oil, thus continually lubricating the gear 33 which will in turn lubricate the gears 32.
- In conclusion, I will state that although numerous details of construction have been shown and described for illustrative purposes, numerous changes may be made within the scope of the invention as claimed without sacrificing the primary advantages thereof.
- I claim:
1. In combination, a pair of spaced parallel flat casings standing upright and adapted to rest on a support, an engine between and supported by said casings, said engine having a pair of driven crank shafts extending into one casing, a horizontal power shaft also extending into said casing, gearing in the latter connecting the crank shafts to said power shaft, a timer or magneto shaft extending into the other casing, and gearing in the latter for driving said shaft.
  2. In combination, a flat upright casing having a horizontally elongated base to rest on a support, a smaller flat upright casing spaced from and parallel to said first named casing, a leg depending centrally from said smaller casing and also adapted to rest on said support, a horizontally elongated cylinder between and secured to both casings, horizontal crank shafts at the ends of said cylinder extending into the first named casing, a pair of pistons in the cylinder for driving said shafts, a gear on each shaft disposed in said first named casing, a horizontal power shaft extending transversely through this casing, a third gear on said power shaft meshed with the aforesaid

gears, a horizontal timer or magneto shaft extending transversely through the smaller casing, and gearing in this casing for driving said timer or magneto shaft.

5. 3. In combination, a substantially triangular flat casing standing upright upon one of its corners and having a horizontal base at such corner to rest on a support, the other two corners of said casing being disposed 10 in the same horizontal plane and rounded, one flat side of said casing having circular openings whose walls coincide with said rounded corners, a pair of parallel crank cases having a cylindrical end inserted and secured in said circular openings in contact 15 with the aforesaid rounded ends, a horizontal cylinder secured at its ends to said crank cases, crank shafts disposed in said crank cases and projecting into the aforesaid casing, a pair of pistons in the cylinder for driving said shafts, a power shaft projecting through the casing, gearing in the latter connecting the crank shafts with the power shaft, and means for supporting the ends 20 of the crank cases remote from the casing.

4. An internal combustion engine comprising a double-ended cylinder having a pair of pistons therein, crank cases at the ends of said cylinder, crank shafts in said 30 cases driven from the pistons, a power shaft disposed transversely below the cylinder and driven by the crank shafts at half the speed of the latter, a valve casing extending from the center of the cylinder and having intake 35 and exhaust valves provided with depending operating stems spaced longitudinally of the cylinder, rigid operating arms projecting horizontally from the lower ends of said stems and disposed in spaced parallel

relation, being positioned longitudinally of 40 the cylinder, cams on the power shaft for intermittently raising said arms to open the valves, a rigid bar extending longitudinally of the cylinder and having its ends rigidly secured to the lower sides of the two crank 45 cases, a rigid arm projecting laterally at right angles from the center of said bar between the valve stems and above the operating arms thereof, and a trio of rigid guide pins depending from said last named rigid 50 arm, one of said pins being disposed between said operating arms while the other two are positioned contiguous to the remote edges of said arms.

5. In combination, a pair of spaced parallel casings standing upright and adapted to rest on a support, a pair of spaced parallel crank cases extending between and secured to the ends of said casings, a cylinder 60 extending between and secured at its ends to said crank cases, crank shafts in said crank cases and extending into one of the aforesaid casings, gearing in this casing, a power shaft extending between and through the casings, said gearing connecting the 65 crank shafts with said power shaft, a magneto or timer shaft extending into the other casing, gearing in this casing for driving said magneto or timer shaft, and pistons in the cylinder for operating the crank shafts. 70

In testimony whereof I have hereunto set my hand in presence of two subscribing witnesses.
